FIG. 2 is an enlarged perspective view of the window operator housing shown in FIG. 1;

FIG. 3 is a top view of the window operator housing shown in FIG. 2;

FIG. 4 is a front view of the window operator housing shown in FIG. 2;

FIG. 5 is a left side view of the window operator housing shown in FIG. 2;

FIG. 6 is a right side view of the window operator housing shown in FIG. 2;

FIG. 7 is a rear view of the window operator housing shown in FIG. 2; and,

FIG. 8 is a bottom view of the window operator housing shown in FIG. 1.

The broken lines running along the perimeter of the bottom of the claim adjacent to the claimed areas in the views represent the boundaries of the design. The additional broken lines of a lever and elements shown on the claim in the figures illustrate the portions of the design that form no part of the claim. None of the broken lines form any part of the claimed design.
